UNITED STATES PATENT OFFICE.

HENRY EVERSMANN, OF CINCINNATI, OHIO.

MAIN VALVE FOR FIRE-EXTINGUISHING SYSTEMS.

SPECIFICATION forming part of Letters Patent No. 700,187, dated May 20, 1902.

Application filed November 9, 1901. Serial No. 81,685. (No model.)

To all whom it may concern:

Be it known that I, HENRY EVERSMANN, residing in the city of Cincinnati, in the county of Hamilton and State of Ohio, have invented certain new and useful Improvements in Main Valves for Fire-Extinguishing Systems; and I do declare the following to be a clear, full, and exact description thereof, attention being also called to the accompanying two sheets of drawings, with the reference-numerals marked thereon, which form also a part of this specification.

This invention relates to certain improvements in valves such as are most frequently used in connection with fire-extinguishing apparatus of the kind where a system of pipes normally empty and provided with outlets in form of sprinkler-heads, spray-nozzles, and similar discharge-openings is supplied with water at the proper time, such supply being controlled by the valve first mentioned. The supply is usually automatic and due to the heat radiated from a fire, in consequence of which the rising temperature melts fusible closing devices, holding the sprinkler and other outlets normally closed, permitting discharge of water after the air held confined in the pipe system has first escaped, which air also by its pressure keeps the aforementioned valve seated, thereby normally excluding the water. It will thus be seen that on one side of this valve there is the air confined in the pipe system, which by its pressure on this valve keeps the same seated, and thereby excludes the water seeking entrance and pressing against it from the other side. For such purpose it is necessary that the air-pressure should at least equal the water-pressure, to which a safe margin of additional pressure must be added. This margin is a higher pressure obtained either by increasing the air-pressure directly or by increasing it indirectly by increasing the area of the valve on the air side. The water-supply is most generally obtained directly from public water-works systems, attachment being had to one of the street-mains thereof, the valve here in consideration being interposed between the supply coming from such street-main and the particular sprinkler-pipe system in communication therewith. In such connection this main valve is subject to

the general water-pressure and any variation thereof, which changes occur very frequently and are due to various causes. Changes 55 take place during the night, when the pressure usually rises. It decreases during the hot season when the demand increases, and in case of emergencies—as, for instance, extensive conflagrations—when the supply is 60 heavily drawn upon. When these fluctuations take place suddenly, particularly from a lower pressure back to the normal or to a higher one, the effect is generally noticeable, more or less, upon any fittings, as valves, 65 cocks, gages, &c., embraced within the service-pipe system. This effect, sometimes known as "water-hammer," is of no particular consequence as to such fittings or valves in fixed positions within their housings and held positively to their seats by mechanical means. In valves of the kind, however, as here in view when the valve is not held to its seat by positive means, but merely by a yielding force, being the pressure of air in the sprinkler-pipe system, the possibility exists that a sudden increase in pressure may momentarily at least disturb the position of the valve by forcing the same from its seat. To overcome this objection as to such valves, being the main 70 valves controlling the supply to a sprinkler-pipe system from the public service and to enable such valves to successfully withstand the shock of a sudden increase in water-pressure, is therefore the main object of my invention.

In the following specification and particularly pointed out in the claims is found a full description of the same, together with its operation, parts, and construction, which latter 90 is also illustrated in the accompanying drawings, in which—

Figure 1 shows a side elevation of my improved valve, or rather its housing, since the former is not visible in this view. Fig. 2 is 95 a vertical section of Fig. 1, being a section through the housing and through the valve inclosed thereby, this latter being in its closed position. Fig. 3 is a view similar to the preceding one, except as to the valve, which is 100 not shown in section and as to its position which is shown in open condition. Fig. 4 is a view similar to Fig. 1 with parts broken away to show a section similar to the one

shown in Fig. 2. Fig. 5 is a horizontal section of the housing, showing the valve in top view. Fig. 6 is a side view of the valve detached, and Fig. 7 shows an implement used at certain times in connection with the valve and for purposes to be presently explained.

10 is the valve-housing, which may be of any suitable size and shape and constructed to be accessible interiorly to permit placing 10 of the valve. In this case the housing is shown cylindrical with tapering ends, which shape is, however, not material. One of the ends is removably connected, forming a head 11 to permit access to the interior. 15 The housing is open at opposite ends, one end receiving the water-supply pipe 12, the other the end of a pipe 13, leading to the sprinkler-pipe system. Normally the water-supply from pipe 12 is prevented from entering the sprinkler-pipe system by a valve contained within housing 10 and held to its seat by the pressure of air confined in the sprinkler-pipe system. By preference I give this valve two seating-contacts, one at 14 20 against a seat 15 and one at 16 against a seat 17, gaskets of yielding material, like rubber or leather, being interposed in each instance. In case of the lower contact this gasket, forming really the seat, is held in position by a 25 ring 18.

In case of the upper contact it is held to the valve corner 16 by means of a ring 19, attached by a screw connection. In case of any reduction of the air-pressure in the sprinkler-pipe system, due to the opening, and escape therethrough of air of any of the outlets therein either directly or indirectly in consequence of the rising temperature due to fire, this valve yields as soon as the water-pressure preponderates over the decreasing air-pressure and is forced away from its seat. If this housing is in a vertical position, as shown, this valve simply drops away, being guided in its movements in either case by 35 guides 21, its drop being limited by projections 22, forming stops for such purpose. The water now passes through the space between the outer edge 14 of the valve and the inside of the housing, as best seen in Fig. 5, and enters pipe 13. In order to lessen the effect of the shock against the valve, due to any sudden increase of water-pressure, I render that side of it exposed toward the water movable independently of the valve proper, the movement being an elastic one, and whereby this part of the valve is permitted to yield, as shown in Fig. 4, to the shock of the water-hammer without necessarily separating the contact of the valve with its seat. 40 This movable face of the valve is obtained by means of a movable head at 23 and is supported at the open end of a housing 24, forming part of the valve, between the contact edges 14 and 16 thereof and within which it 45 is yielding held against an inwardly-projecting flange 25. This elastic pressure, which might be provided by a fluid intro-

duced into housing 24, is preferably furnished by a spring 26 therein. Its action is substantially that of a buffer or cushion, and at a 50 sudden increase it will yield, when it is expected that its resistance will exhaust the effects of the sudden shock accompanying such increase without permitting this latter to affect the seating-contact of the valve by 55 vibrating or jarring the same. As will be seen, particularly in Fig. 4, this yielding of head 23 does not admit passage of water, since the valve remains still closed, there being no part of this latter subject to contact 60 with and pressure of the water, such contact being limited to the outer surface only of the movable head 23. Leakage into housing 24 is prevented by suitable packing 27, carried by this head 23. To permit taking up of 65 wear at the valve-seats, one of them, in this case seat 17, is supported adjustably, the adjustment being by means of set-screws 28. These latter are accessible from the outside, so that it is not necessary for purpose of such 70 adjustment to interrupt the service by taking the valve-housing apart. Leaking at this movable valve-seat is prevented by packing 29, held in place by a ring 30 against a flange 30'. 75

When setting and charging this system, it becomes necessary to hold the valve closed by positive means until sufficient air is charged into the sprinkler-pipe system to raise a pressure able to hold it seated against 80 the water-pressure. For such purpose, the water having been shut off by means of the general stop-cock in pipe 12 (not shown) and controlling all branch connections through mains, a cap 31 is removed above the valve 85 and the upper part of the housing thereof, which permits insertion of an implement 32 and engagement of the lower screw-threaded end thereof with a correspondingly-threaded socket 33 in movable head 23. By means of 90 a nut 34 this rod, with attached valve, is drawn outwardly and so held with the valve against its seat, thus shutting out the water until sufficient air is introduced on the other side. This introduction of air is at 95 35 and 37 are hand-holes to permit access to the valve for any further manipulation whenever necessary. In order to prevent all possibility that removal of this rod might be forgotten, which would render automatic opening of the 100 valve impossible, I provide an electrical signal, which by its action shows the condition 105 of the valve. It may be a bell-signal or an indicator. For such purpose I provide two contact-pieces, connected to binding-posts 38 110 and 39, and one (shown at 41) being elastic. They are held normally apart by a lateral projection 42 on cap 31, when this latter is in 115 position after the apparatus is properly prepared, but on removal permits contact and 120 operates the signal.

Having described my invention, I claim as new—

1. A main-valve mechanism for a fire-extin-

guishing apparatus, consisting of a housing communicating at one end with a water-supply pipe and at the other with a sprinkler-pipe system, a valve contained in this housing and a seat for it in this latter and against which it is normally held by air under pressure contained in the sprinkler-pipe system, that part of the valve-surface exposed to the action of the water and in contact therewith having an independent movement on the valve without affecting the position of this latter and being held in normal position by a yielding pressure.

2. A main valve for fire-extinguishing apparatus to be interposed between an air-charged sprinkler-pipe system and a water-supply pipe therefor and intended to normally prevent such supply, the same being provided with an elastic cushion on that side of it which is in contact with the water and subject to the pressure thereof, such cushion being capable of a movement independent of the valve and without affecting at such time the position thereof.

3. A main valve for fire-extinguishing apparatus to be interposed between an air-charged sprinkler-pipe system and a water-supply pipe therefor and intended to normally prevent such supply, the same having a housing on the water side and a head fitted

thereto with an elastic pressure and in a manner to be capable of a movement independent of the valve and without affecting at such time the position thereof.

4. A main valve for fire-extinguishing apparatus to be interposed between an air-charged sprinkler-pipe system and a water-supply pipe therefor and intended to normally prevent such supply, the same having two seating-contacts at 14 and 16, a housing 40 24 between them and an elastically-supported head 23 therein.

5. In a valve mechanism for fire-extinguishing apparatus involving an air-charged sprinkler-pipe system and a water-supply pipe therefor, the combination of a valve-housing interposed between the two and in communication with each, two valve-seats therein, a valve for them adapted to have simultaneously seating-contact with both seats 50 and bolts 28 accessible from the outside whereby the position of one of these valve-seats may be adjusted within the valve-housing.

In testimony whereof I hereunto set my signature in the presence of two witnesses. 55

HENRY EVERSMANN.
